UNITED STATES PATENT OFFICE.

JOSEPH W. HORTON, OF BLOOMFIELD, NEW JERSEY, ASSIGNEE TO WESTERN ELECTRIC COMPANY, INCORPORATED, OF NEW YORK, N. Y., A CORPORATION OF NEW YORK.

OSCILLATION GENERATOR.

Application filed July 18, 1924. Serial No. 726,683.

This invention relates to oscillation generators and more particularly to space discharge tube oscillators having means for preventing frequency variations of the generated oscillations.

In space discharge tube oscillators as heretofore designed, the output circuit has been coupled to the input circuit for the purpose of producing regeneration by means of reactive impedance devices such, for example, as condensers or transformers. These reactive coupling devices are known to have an influence upon the frequency of oscillations generated by the oscillator and to produce changes in its frequency by virtue of changes in their reactance resulting from any cause such, for example, as changes in temperature, dielectric strength or permeability of the parts of these devices. This results in the serious disadvantage that constant frequency oscillations can not be produced by an oscillator subjected to temperature or other variations nor can any simple adjustment be made to restore the system to stability at a readily predictable frequency since an adjustment of one quantity in the system is accompanied by a general readjustment of all the others.

In accordance with the present invention the elements which are designed and intended to control the frequency are so associated with other elements which might, because of their varying characteristics, affect the frequency that mutual reaction between the frequency control elements and the other elements is practically eliminated.

The question of frequency stability has recently taken on considerable importance because the need for currents of accurately known frequency is being felt in all branches of the electrical communication art particularly in the field of multiplex transmission over wires by means of carrier currents and in radio broadcasting.

An object of the present invention is to generate oscillations of constant frequency.

Another object is to control the frequency of an oscillation generator independently of reaction therefrom upon the control element thereof.

A further object is to segregate the frequency control elements of an electrical oscillator from other elements thereof.

A still further object is to control the power gain and phase shift of waves in an

oscillation generator whereby oscillations of only a desired frequency may be generated.

A feature of the invention relates to a space discharge tube oscillator having a frequency-control element, which is electrically independent of changes in the amplifying element.

Another feature relates to a space discharge tube oscillator having its frequency controlled by means of an element which is coupled to the amplifying element by means of non-reactive elements.

Another feature of the invention relates to an oscillation generator comprising a resonant circuit for controlling the frequency of oscillations which is electrically segregated from the amplifying element.

An additional feature concerns a space discharge tube oscillator having its frequency controlled by a piezo electric crystal arranged to be independent of reaction from the amplifying element.

Another feature relates to a space discharge tube oscillator in which the frequency control element comprises an electrically driven tuning fork, the frequency of which is maintained independent of changes in the amplifier circuit.

A still further feature is a space discharge tube oscillator in which the frequency control element comprises a filter network resistance coupled to the amplifier.

This invention comprises a generator of oscillations having provided a frequency control element the parts of which are maintained substantially independent of influence from other elements of the system to prevent changes in frequency caused by reaction upon this element of other elements of the system. The oscillation generator comprises an energy amplifying element and a frequency control element. Means is also provided for supplying energy to a load device. The frequency control element may

consist of one or more component elements, at least one of which is so arranged as to have a frequency characteristic that is substantially unaffected by that of the associated amplifier element. The frequency control element is arranged to be supplied with only a small portion of the energy output from the energy amplifying element.

By virtue of this fact the effect of fluctuations in the energy output of the oscillator upon the frequency control element is made

negligible. In addition, the frequency control element or parts thereof are coupled to the energy amplifying element by means whose energy transfer efficiency remains unchanged with variations in the frequency of the energy. Hence, the frequency control element is rendered substantially unaffected by changes in reactance of other parts of the circuit tending to cause changes of frequency and also by changes in amplitude of the energy supplied thereto.

In the drawings:

Fig. 1 is a circuit diagram of a space discharge tube oscillator having its frequency controlled by a series resonant circuit resistance coupled thereto.

Fig. 2 is a circuit diagram of an oscillation generator similar to that of Fig. 1 wherein the frequency control element is a filter network.

Fig. 3 is a circuit diagram of a space discharge tube oscillator having its frequency controlled by a resistance coupled piezo electric crystal.

Fig. 4 is a circuit diagram of an oscillation generator controlled as to frequency by means of a tuning fork.

Referring to Fig. 1, an oscillation generating system is illustrated which includes an energy amplifying element 10 and a frequency control element 11. The amplifying element comprises space discharge tubes 12 and 13 arranged in tandem and coupled by means of a condenser 14 and resistance 29. The input circuit of tube 12 and the output circuit of tube 13 are coupled by means of a feed back circuit 9. The circuit 9 includes the frequency control element 11 connected between coupling resistances 16 and 19.

The input circuit of tube 12 includes in series a grid polarizing battery 15 and resistance 16 and is connected to the grid and cathode of the tube. The output circuit of tube 13 includes condenser 17, high resistance 18, and low resistance 19 in series and is connected to the anode and cathode of the tube. Leads 20 and 21 are associated with this output circuit for supplying any desired energy consuming load device. Lead 20 includes a resistance 65. The frequency control element 11 includes an adjustable inductance 22 and an adjustable capacity 23 connected between terminals of resistances 16 and 19. The opposite terminals of these resistances are connected together. Space current is supplied to tubes 12 and 13 by sources 24 and 25, illustrated as batteries, in series with choke coils 26 and 27 respectively.

The input circuit of tube 13 is coupled to the output circuit of tube 12. Suitable average polarizing potentials are supplied to the grids of tubes 12 and 13 by batteries 15 and 28 the latter being in series with resistance 29.

The resistance 19 is so proportional with respect to the impedances of other portions of the connected circuits that sufficient energy is transmitted to the control element 11 to maintain oscillations. In other words 70 it is designed with respect to the value of resistance 18 and the impedance of the load circuit connected to leads 20 and 21 due allowance being made for possible variations of these impedances in use. 75

Resistance 65 in lead 20 is large as compared to any load impedance connected to leads 20 and 21 and by this means changes in the output power are rendered negligible in their effect in producing variation of the 80 damping of the inductance 22. Hence their effect in changing the resonant frequency of the tuned circuit is negligible. By the use of these coupling resistances 16 and 18 and 19 the system can be adjusted so that the 85 several elements operate at that portion of their characteristics which insures maximum stability. By using resistance coupling instead of reactive coupling the parts of the amplifier element may be adjusted without 90 substantial reaction upon the frequency controlling element. Also by adjustment of the frequency controlling element, as by means of condenser 23 or inductance 22, the oscillator may be caused to oscillate at an easily 95 predictable frequency.

In order to reduce the phase shift of energy through the amplifier element 10 the value of resistance 29 is made large as compared to the reactance of condenser 14. 100

In the operation of the system shown in Fig. 1 energy is supplied from the output circuit of tube 13 through the coupling resistance 19 to resonant element 11 and from this element energy of the frequency determined thereby is transmitted through coupling resistance 16 to the input circuit of tube 12. This energy is amplified by tube 12 and transmitted through coupling condenser 14 to the input circuit of tube 13. 110 Tube 13 produces further amplification of the energy and it is again supplied from the output circuit through the resonant element 11 and the coupling resistances to the input circuit of tube 12. 115

The resonant circuit 22-23 is designed so that the phase of current therein changes with frequency at a high rate, hence, only a small change of frequency in the circuit is required to compensate for phase changes in 120 other elements of the system.

Condenser 17 is provided to prevent the flow of direct current from battery 25 through the load circuit connected to leads 20 and 21.

In Fig. 2 is illustrated an oscillation generator which comprises an energy amplifying element 10 which is identical with the element 10 shown in Fig. 1. It also comprises a frequency control element 30 here 130

illustrated as a filter network. The element 30 is connected between coupling resistances 16 and 19 in the feed-back circuit 9 connecting the input circuit of tube 12 and the output circuit of tube 13. The filter 30 includes series anti-resonant elements 31 and shunt capacity elements 32. This network is also designed to have a high rate of change of attenuation and phase with frequency in the region wherein it is designed to operate and hence renders the frequency highly independent of changes in the amplifier element or circuit as already explained. The high rate of change of phase with frequency variation is an important consideration.

The operation of this system is substantially identical with that of Fig. 1 and therefore need not be repeated.

20 In Fig. 3 an oscillation generating system is illustrated in which one part of the principal frequency control element 33 is a piezo electric device. This device may consist of a crystal 39 cut from quartz in the 25 shape of a parallelepiped and having metallic plates 40 adjacent to two opposite sides. The plates 40 are connected to terminals of resistances 16 and 19 included in the feed-back circuit 9 connected respectively to input 30 and output circuits of tubes 12 and 13. A secondary frequency control element included in the system is a series resonant circuit 34-35 arranged to couple the tubes 12 and 13 of the amplifier element. In 35 series with the resonant circuit 34-35 is a series arrangement of a condenser 36 and a resistance 37. An additional coupling resistance 38 is connected to the junction between resistance 37 and inductance 34 and 40 to the cathodes of tubes 12 and 13. The resistances 37 and 38 are provided to render the impedance of the tube output circuit substantially non-reactive to prevent substantial phase changes in the current flowing therein. The value of these resistances is therefore large as compared to the reactance of condenser 36.

45 The piezo electric crystal 39 has a plurality of frequencies at which it will produce a response, or in other words, vibrate. It is a characteristic of such a crystal that on account of its low damping at the frequencies to which it responds it causes oscillations to be maintained at substantially 50 constant frequency. However, in order to determine the particular one of its responsive frequencies at which the crystal shall vibrate the series resonant circuit 34-35 is provided as a supplementary frequency determining element. The circuit 34-35 is tuned to approximately the responsive frequency of the crystal at which it is desired to generate oscillations. The action of this resonant circuit is then such that preference 55 is given to that particular resonant fre-

quency of the crystal 39. In other words, at the desired frequency the impedance of the resonant circuit 34-35 is low, whereas at the other resonant frequencies of the crystal 39 the impedance of the resonant circuit 70 34-35 is very high, hence it serves to permit the generation of oscillations at the desired frequency and to prevent oscillations at other responsive frequencies of the crystal. 75 By adjusting variable condenser 35, the resonant circuit 34-35 may be tuned so as to cause the generation of oscillations at any one of the desired frequencies at which the crystal 39 is responsive. The piezo electric device then operates to maintain the oscillations at this selected frequency within very narrow limits. The coupling resistances 16 and 19 serve to supply the necessary energy from the output circuit to the input circuit, 80 to cause oscillation. Changes in the load connected to leads 20 and 21 are prevented from producing changes in the frequency of the oscillator, by their action upon the frequency controlling element, by means of resistance 65, since a negligible percentage of 85 the fluctuation is applied to the resonant piezo electric device.

85 An oscillation generating system is illustrated in Fig. 4 which includes as a frequency control element a tuning fork 41. 90 The tuning fork 41 is arranged to be maintained in vibration by driving magnet 42, the winding of which is connected in series with a polarizing battery 66 to the terminals of resistance 19 in the output circuit of 95 amplifier tube 43. If desired battery 66 may be omitted and the magnet 42 may be polarized by means of current from battery 25 by closing switch 67. As another alternative it may have a permanent magnetic core. 100 The resistance 19 in this system may be relatively large. A pick-up magnet 60 is arranged adjacent to the prongs of tuning fork 41 and has its winding connected to the resistance 16 included in the input circuit 105 of the space discharge tube 44. The core of magnet 60 is normally magnetized. The magnetization may be produced by providing a permanent magnetic core or by means of a battery 45 connected in series with the 110 winding of magnet 60 as shown.

115 The amplifier element in this system includes space discharge tubes 43 and 44 in tandem with space discharge tube 46. Tubes 43 and 44 are coupled to the output and input circuits respectively of tube 46. Condensers 47 and 48 together with inductances 50 and 52 respectively form resonant coupling circuits between tubes 43 and 46 and, 120 44 and 46 respectively. To reduce the phase 125 shift of energy through the amplifier element resistances 49, 55, 51 and 56 are provided as already explained. A condenser 57 is connected in series with a resistance 49 and an inductance 50 between the anode of 130

tube 46 and the grid of tube 43. A condenser 58 is connected in series with resistance 51 and inductance 52 to the anode of the tube 44 and the grid of tube 46. Condensers 57 and 58 are provided to prevent current from batteries 59 and 61 from flowing in the input circuits of tubes 43 and 46. Batteries 53 and 54 are provided for supplying suitable average polarizing potentials to the grids of tubes 43 and 46. Shunt resistances 55 and 56 are connected to the junctions between resistance 51 and inductance 52 and resistance 49 and inductance 50 respectively, and to the cathodes of tubes 43, 44 and 46.

The circuit of Fig. 4 has its frequency controlled by the tuning fork 41 in the same manner as the circuits of Figs. 1, 2 and 3 had their frequencies controlled by means of resonant elements 11, 30 and 33. Energy supplied from the output circuit of tube 43 is transmitted through resistance 19 to the winding of magnet 42. The magnet 42 acting upon the magnetic prongs of fork 41 causes the fork to vibrate at its natural frequency. The vibration of the prongs of fork 41 adjacent to the core of magnet 60 induces an alternating current in the winding of the magnet the frequency of which corresponds to the frequency of vibration of the fork 41. The energy of this current is transmitted through coupling resistance 16 to the input circuit of tube 44. This energy is amplified by means of amplifier tubes 43, 44 and 46 and again supplied from the output circuit of tube 43 to the driving magnet 42. It is thus seen that sustained oscillations of constant amplitude and of constant frequency as determined by the natural frequency of the fork 41 may be generated by this system. The coupling resistances 16 and 19 perform the same function in this arrangement as in the circuit of Figs. 1, 2 and 3. In this instance the resistance 19 may be considerably larger than in the other circuits in order to allow sufficient current to drive the fork to pass to magnet 42. The changes in the current supplied to magnet 42 caused by variations of the load on the oscillator or otherwise are increased by increase of resistance 19 but because of the great inertia of the tuning fork these changes are not increased sufficiently to affect its frequency of vibration. The tuning fork 41 is designed to have a high rate of phase change with frequency the same as the control elements of the other figures in order that a change of phase in the amplifier element may be compensated by a small change of frequency of the fork.

Although this invention has been illustrated as embodied in certain specific arrangements it is to be understood that its limitations are defined only by the scope of the appended claims.

What is claimed is:

1. An oscillation generator which comprises an amplifying element, a frequency control element, and non-reactive means for coupling said control element to said amplifying element. 70

2. A system in accordance with claim 1 in which the frequency control element produces a large phase change per unit frequency change. 75

3. An oscillation generator which comprises an amplifying element, a frequency control element, and means for coupling said elements including non-reactive devices. 80

4. An oscillation generator which comprises an amplifying element, a resonant frequency control element, and means for coupling said elements to cause the generation of oscillations which comprises substantially wholly resistance. 85

5. An oscillation generator which comprises a space discharge tube amplifying element, a frequency control element, and means comprising non-inductive resistance for coupling said elements to cause the generation of oscillations. 90

6. An oscillation generator which comprises a space discharge tube amplifying element, a resonant frequency control element, and non-reactive means for coupling said elements to cause the generation of constant frequency oscillations. 95

7. An oscillation generator which comprises a space discharge tube amplifying element, a frequency determining element, having a natural frequency of response, means for supplying oscillations to a load, and means for coupling said elements in energy transfer relation whereby said response frequency is held substantially fixed during variations of energy in said generator. 100

8. In an oscillation generator, an energy amplifying element and a frequency controlling element, said frequency controlling element comprising a series resonant circuit, 110 and means coupling said elements comprising non-reactive impedances.

9. In an oscillation generator, an energy amplifying element comprising a plurality of three-electrode space discharge tubes, a frequency controlling element, and means for coupling said frequency controlling element to an input and an output circuit of said tubes, said coupling means comprising non-reactive impedances. 115

10. An oscillation generator which comprises an amplifying element, a frequency control element, and resistance couplings associating the input and output circuits of said amplifier with said frequency control element, whereby said frequency control element is only negligibly affected by changes in condition of said amplifying element. 125

11. In combination, an incoming circuit and an outgoing circuit, and means for cou- 130

pling said circuits comprising a path including a resistance, a capacity and an inductance in series, and shunt resistances connected to electrically separate points in said path.

5 12. In combination, a wave generating device and a load circuit, means for preventing reaction of said load circuit upon said device comprising a path including resistance, capacity and inductance elements in series and 10 resistance elements in shunt.

13. In combination, two electrical circuits, one of said circuits being arranged for connection to a load device, means for coupling said circuits comprising a series tuned circuit connected between shunt resistances and 15 another resistance connected in series with

said tuned circuit, said series resistance being large as compared to one of said shunt resistances.

14. In combination, two electrical circuits, 20 one of said circuits being arranged for connection to a load device, means for coupling said circuits comprising a resonant circuit connected between shunt resistances, and a series resistance connected outside of said 25 shunt resistances, said series resistance having a value which is large compared to said shunt resistances.

In witness whereof, I hereunto subscribe my name this 16th day of July A. D., 1924.

JOSEPH W. HORTON.
